UNITED STATES PATENT OFFICE.

HERMAN T. C. KRAUS, OF BROOKLYN, NEW YORK, ASSIGNOR TO GEORGE E. SANBORN, OF CHICAGO, ILLINOIS.

PAPER-CUTTING MACHINE.

SPECIFICATION forming part of Letters Patent No. 296,184, dated April 1, 1884.

Application filed February 23, 1883. (No model.)

To all whom it may concern:

Be it known that I, HERMAN T. C. KRAUS, a naturalized citizen of the United States, residing at No. 15 Stagg street, Brooklyn, in the county of Kings, State of New York, have invented a new and useful Paper-Cutting Machine, (for which I have obtained no patent whatever,) of which the following is a specification.

10 My invention relates to improvements in paper-cutting machines in which a knife operates from above upon a table in cutting, and in which the paper is firmly clamped during the process of cutting; and the principal object of my invention is to provide means for 15 automatic or self clamping by means of the same power that is employed in operating the knife. I attain this and other objects by the mechanism illustrated in the accompanying drawings, in which—

Figure 1 is a sectional view cut at one side of the center, showing all the parts connected with the clamping and cutting. Fig. 2 is a total front view of the machine. Fig. 3 is a 25 top view, looking down upon the section cut at line *x x*, and showing gear G, Fig. 2. Fig. 4 is a sectional view of the clamping devices, cut at right angles to that of the same parts shown in Fig. 1. Fig. 5 is a vertical section from the 30 top of the table, cut through the pivotal points of the main and some subordinate levers on line *y y*, Fig. 1. Fig. 6 is an elevation of the yoke in which the crank-shaft has its bearing, the driving-shaft bearing and frame being in 35 section.

Similar letters refer to similar parts throughout the several views.

I avoid the objections made to self-clamping paper-cutters in which the knife moves up to 40 the paper from below, and to some extent is concealed by the paper when in the act of cutting, by placing the knife above and moving it down upon the paper in plain sight, and by operating the clamp also from above independently in advance of any movement of the 45 knife, and while it is at rest, and without interfering with any subsequent movements of the cutting apparatus and its operating mechanism.

A is the working-arm, operated (one on each side of the machine) by the crank C on crank-shaft S', upon which the driving-gear G is placed, and into which the pinion P on the driving-shaft S works. The arm A has for its primary fulcrum the lever-shaft S', both ends 55 of which rest in the curved slot T, which is in the main frame F. The crank-arm A' is provided with a roller, R, which works in the slot T' and operates the working-arm A. At its opposite end the arm A is connected with the 60 knife-bar B and knife K through the connecting-rod D, the cross-bar B', and the connecting-rod D'.

U is the driving-pulley on the shaft S, and U' a fly-wheel on the same shaft. 65

M is the clamp, which is operated in two ways: first, for purposes of adjustment, by or through the arm A'; and, second, during the cutting by the arm A and the intermediate devices. 70

B² is the clamp-bar, which sustains the clamp in its uppermost position upon the pin I, which last is secured in the lower end of the link L, and moves in the slot T' in the lower part of the link L'. The link L' is one limb 75 of a toggle, the other limb being L², the upper end of which works upon the pin I², secured in the clamp-bar B², and thereby sustains the clamp and clamp-bar in the uppermost position when the arm A' is in the position shown 80 in Fig. 1, where it is held by a pin, I³, or in any usual manner, for that purpose. When the arm A' is released from the control of the pin I³, the clamp M will drop automatically as 85 far as the table-top F', unless a pile of paper, having been placed thereon, intervenes and stops it. This movement is caused by the weight of the clamp and its attachments, and carries the associated parts with it, as follows: The toggle-links L' and L², connected at the 90 pin I⁴, whereto the link L³ is also attached, in dropping, are partially controlled by the link L³, and bent slightly out of a straight line thereby, the other end of the link L³ being still held nearly stationary upon the pin I⁵. 95 The preliminary clamping of the paper is thus accomplished. The clamp having once dropped to its lowest point, or to any inter-

mediate point, may be again raised by means of the arm A^3 , and there held by the pin I^3 . In fact, the clamp is under the control of the arm A^3 . When the clamp M has reached and rests upon the paper, the driving-shaft may be set in operation, in any ordinary way, to operate the knife and knife-bar. The first effect of this movement is to raise the slotted end of the arm A , and thereby still further depress the clamp M . This is done through the connecting-rod D^2 , crank-bar C' , link L^3 , and toggles L^2 and L' , and before there is any considerable movement of the knife, for the reason that the long arm of the crank-lever C' is attached to the toggles, and the short arm to the connecting-rod D^2 , which gives a materially-increased movement to the clamp and bar B^2 . The clamp will not be moved to any considerable extent if the arm A^3 has been previously released, as described; but if it has not been, then the toggles and connections being drawn toward the positions shown in dotted lines, the clamp will be brought down automatically and independently of the arm A^3 by the arm A . The link L' , being slotted at its lower end, permits the movement of the toggles toward the positions of the dotted lines, whatever variable thickness of paper may be under the clamp, and therefore the movements of the rest of the machinery cannot be checked by this member of the toggle, as it would be if there were no slot for the pin I to move in.

The subsequent clamping during the cutting is divided into two parts, both of them under the control of the arm A , as follows: first, through the connecting-rod D^3 and arm A^4 ; and, second, through the arm A^5 , link L^4 , and toothed segment-lever arm A^6 , the teeth of which take in the teeth shown on the clamp-bar B^2 . The operation is as follows: On starting the driving-shaft, raising the slotted end of the arm A , and depressing its other end, the connecting-rod D^3 draws down the arm A^4 , forcing its roller R' against the back side of the clamp-bar B^2 , and the roller R^2 , at its other end, against the far side of the slot T^3 , which inclines inward and upward, so as to force the roller R' with an increasing pressure against the clamp-bar B^2 as the arm A continues to move. The clamp-bar B^2 is held by guide-blocks E , so that the roller R' will have sufficient grip on the clamp-bar to hold the paper for cutting. In some cases—as where the paper is very hard to cut—still further clamping-pressure is required; and this I attain by means which I will now describe. The moment the knife meets with such resistance as to stop or delay the cutting action of the knife, the continued movement of the crank C will lift the arm A and its shaft S^2 , thereby changing the fulcrum from that shaft to the pin I^6 , which receives the connecting-rod D , thereby causing the arm A^5 to

force the link L^4 against the roller R^3 , thereby pushing the toothed segment-arm A^6 (the pin I^6 of which moves in a slot, T^4 , for that purpose) into engagement with the teeth of the clamp-bar B^2 . Continued upward movement of the slotted end of the arm A causes the arm A^6 to turn on its pin I^6 , and, pushing powerfully against the roller R' , as well as downward, to force the clamp down upon the paper with additional pressure when required. The slot T relieves the arm A and its shaft S^2 during this movement, and eventually the shaft S^2 becomes again the fulcrum, whereby the other end of the arm A , the connecting-rod D , and the knife are further depressed and the cutting is finished. The continued movement of the driving-shaft reverses the arm A and restores it and its attachment to the positions shown in Fig. 1. There are two arms A , and attachments also in duplicate, in each side of the machine, as shown in Fig. 2.

The knife-bar is shown suspended in the usual manner on the links W W ; but any equivalent devices may be used for giving the diagonal cut.

I have provided for the adjustment of the knife, as it wears, by means of the screws and nut N N at each end thereof through and upon the intermediate cross-bar, B .

The arm A^5 is not rigid, but has a slight motion. It should be made strong, as it sustains, through the shaft S^2 , substantially the entire upward pressure of the arm A in cutting.

The link L^5 connects the link L and arm A^3 .

I claim as my invention—

1. In a paper-cutting machine, the clamp supported by the clamp-bar B^2 , and the links L' and L^2 , resting upon the pins I , in combination with the link L and arm A^3 , for the purpose of controlling the preliminary adjustment of the clamp, substantially as shown and described. 105

2. The arm A , connecting-rod D^2 , crank-lever C' , arm L^3 , toggle-links L' and L^2 , and the clamp-bar B^2 , in combination, for the purpose of controlling the adjustment of the clamp.

3. In a paper-cutting machine, the arm A and shaft S^2 , in combination with the arm A^5 , link L^4 , roller R^3 , and the toothed segment-arm A^6 . 110

4. The combination of the arm A , connecting-rod D^3 , arm A^4 , rollers R' and R^2 , the latter working in the inclined slot T^3 , and clamp-bar B^2 , asset forth. 115

5. In a paper-cutting machine, arm A , arm A^5 , link L^4 , toothed segment-arm A^6 , pin I^6 , and toothed clamp-bar B^2 , in combination, as 120 and for the purpose set forth.

HERMAN T. C. KRAUS.
